UNITED STATES PATENT OFFICE.

JOSEPH H. JOHNSON, OF LOS ANGELES, CALIFORNIA.

PONTOON BRIDGE.

Application filed July 1, 1925. Serial No. 40,908.

My invention relates to and has for its purpose the provision of a pontoon or floating bridge having a plurality of pontoons associated with each other in such manner as to effect a wide and even distribution of any load imposed thereon whereby a bridge constructed in accordance with my invention is capable of supporting and permitting movement thereover of excessive loads such as locomotives or cars without the liability of collapsing or such deformation as to impede the movement of the load across the bridge.

I will describe only one form of pontoon bridge embodying my invention and will then point out the novel features thereof in claims.

In the accompanying drawings—

Figure 1 is a fragmentary view showing in side elevation one form of pontoon bridge embodying my invention.

Figure 2 is a view showing in plan the bridge shown in Figure 1.

Figure 3 is a fragmentary perspective view of the bridge with the connecting beams omitted.

Referring specifically to the drawings, in which similar reference characters refer to similar parts in each of the views, my invention in its present embodiment comprises a series of pontoons P arranged in side by side relation and said pontoons being of elongated form to displace a large quantity of water and thus have great buoyancy. As shown in Figures 1 and 2, the upper side of each pontoon is of anticlinal form with any two adjacent pontoons connected by a trussed frame T hingedly secured to the apexes of the pontoons as indicated at 15.

Each trussed frame T is of substantially frusto-pyramidal form with the sides converging upwardly from the pivots 15. Each trussed frame is of skeleton form and is made up of metal beams rigidly connected to each other and arranged to withstand any excessive strains and stresses to which it might be subjected while in use. As illustrated to advantage in Figure 3, the construction and arrangement of the trussed frames is such that a continuous passage-way is formed through the trussed frames and transversely of the pontoons, and to permit the passage of vehicles therethrough, a suitable supporting platform may be provided on the bottom of the trussed frame.

However, in the present instance I have shown the bridge constructed for the passage of trains thereover and to this end longitudinal ties 16 are arranged at the bottom of each trussed frame to support transverse ties 17 and upon the latter are supported the rails of tracks over which the trains are adapted to move. These rails are made in sections, each section being of a length corresponding to the width of any one trussed frame so that adjacent rail sections are supported independently of each other to allow the necessary vertical movement of adjacent trussed frames.

In order to effect a wide and even distribution of any load imposed on the trussed frames and to thus prevent undue depression of any one or group of pontoons so that the trussed frames will be maintained substantially in horizontal alignment, I provide at opposite sides of the trussed frames a plurality of beams all of which extend upwardly from the pivots 15 for pivotal and slidable connection with the upper portions of the trussed frames as indicated at 18. When considering the beams for any one pontoon it will be seen by reference to Figure 1 that a pair of beams 19 extend upwardly from the corresponding pivot 15 for pivotal and slidable connection at their upper ends with other trussed frames than those supported on the pontoon, while extending from the same pivot is another pair of beams 20 having their upper ends pivotally and slidably connected to the next trussed frames at the corners of the confronting sides thereof. As illustrated in Figure 2, the arrangement of the beams is such that those of any two adjacent pontoons cross each other to permit of their connections to the trussed frames in the manner described and to allow of the separate and independent movement of each.

In practice, the anticlinal surfaces of the pontoons and the converging sides of the trussed frames permit of limited movement of the trussed frames vertically when trains or other vehicles are moving over the bridge, and with a load imposed of any one truss, it will be clear that the downward force exerted on the trussed frame will tend to lower the respective pivots 15 thereby exerting a downward pull on the beams connected thereto thus tending to lower adjacent trussed frames against the buoyancy of the

pontoons and thus distributing the load over several of the trussed frames and pontoons so that only a minimum depression is effected of the trussed frame upon which the load is directly supported. The sliding pivots 18 are designed to allow the pontoons to respond to the undulations in the surface of the water without actuating the beams to the extent of setting up any strain or stress 10 on the beams or trussed frames, it being understood that the sliding pivots permit limited longitudinal movements of the beams before actuating the trussed frames.

Although I have herein shown and described only one form of pontoon bridge embodying my invention, it is to be understood that various changes and modifications may be made therein without departing from the spirit of the invention and the 15 spirit and scope of the appended claims.

What I claim is:

1. A floating bridge comprising pontoons arranged side by side, and trussed frames supported on and pivotally connected to adjacent pontoons.

2. A floating bridge comprising pontoons, and trussed frames supported on and pivotally connected to adjacent pontoons.

3. A floating bridge comprising pontoons arranged side by side, trussed frames bridging the pontoons and pivoted thereon, and means connecting the pontoons and trussed frames whereby a load imposed on any one trussed frame will be distributed to and over a plurality of trussed frames and pontoons.

4. A floating bridge comprising pontoons arranged side by side, trussed frames bridging the pontoons and pivoted thereon, and beams pivotally connecting the trussed frames and pontoons in such manner that a load imposed on any one trussed frame will be distributed to and over a plurality of pontoons and trussed frames.

5. A floating bridge comprising pontoons, trusses bridging the pontoons and pivoted thereon, and beams having slideable and pivotal connections with the trussed frames and

pivotal connections with the pontoons in the manner and for the purpose described.

6. A floating bridge comprising pontoons arranged side by side, trussed frames bridging the pontoons and hingedly connected thereto, and beams pivoted on the pontoons at the hinged points of connection of the latter with the trussed frames and pivotally and slidably connected to the trussed frames.

7. A floating bridge comprising pontoons arranged side by side, trussed frames bridging the pontoons and pivoted thereon, and beams extending upwardly from the opposite ends of the pivotal connections between any one pontoon and the corresponding pair of trussed frames and in opposite directions, said beams being pivotally connected to trussed frames adjacent the aforementioned pair of trussed frames.

8. A floating bridge as embodied in claim 7 wherein the pivotal connection between the beams and trussed frames is slideable for the purpose described.

9. A floating bridge as embodied in claim 7 wherein the pivotal connections between the beams and trussed frames are slideable and the beams extending in opposite directions from the connections are arranged in pairs.

10. A floating bridge as embodied in claim 7 wherein the pivotal connections between the beams and trussed frames are slideable and the beams extending in opposed directions from the connections are arranged in pairs with the beams of each pair connected to one truss frame at different points.

11. A floating bridge as embodied in claim 7 wherein the pivotal connections between the beams and trussed frames are slideable and the beams extending in opposed directions from the connections are arranged in pairs with the beams of each pair connected to one truss at different points equidistant from the longitudinal axis of the truss frame.

JOSEPH H. JOHNSON.
